METHOD AND APPARATUS FOR MAKING
METAL STRIPKirtland C. Gardner, Coraopolis, Pa., assignor to
United Engineering & Foundry Company,
Pittsburgh, Pa., a corporation of Pennsylvania

Application October 3, 1936, Serial No. 103,950

21 Claims. (Cl. 80—31.1)

This invention relates to the making of metal blanks and slabs and, more particularly, is concerned with apparatus and methods for the commercial manufacture of steel strip.

It is inconvenient and metallurgically very difficult to cast ingots wide enough to produce wide sheets and strips without cross rolling. The maximum ingot width which is considered practical is in the neighborhood of 65 inches, and sheets and strip are required to widths approaching 100 inches. Heretofore, these wide sheets and strip have been produced by rolling an ingot not over 65 inches wide into a slab approximately 60 inches wide, shearing the slab, reheating it, rolling it broadside to the desired width, and then rolling it longitudinally to the desired thickness. This method of rolling requires that the slabs be broadside rolled after reheating, which means that they cannot be longer than can be handled by a roll of practical length; in other words, they are practically limited to some 8 feet in length, and for broadsiding a very large and expensive mill must be provided, which has no other function except to give perhaps a single pass of very short duration. Another disadvantage of this method is that the time required for broadsiding after reheating could very much better be used in elongating the slab, since the usual requirement is to reduce these slabs to quite thin material and to perform this operation quickly because finishing at a suitable temperature is quite important.

It will be appreciated that these known methods and apparatus for manufacturing metal strip involve tremendous initial and production costs by the very fact that so many different types of mills are required, many of which will be idle during the formation of the strip on the other mills in the operation. In addition, a relatively large number of men are required to control the operation of the various machines, and difficulty is experienced in making the operation of the various mills continuous to improve the efficiency thereof. This is particularly true in the method of making metal strip by first passing the slab through a broadside mill and then through a reversing universal mill in that the broadside mill must remain idle during the entire rough-sheeting operation of the universal mill which, of course, means high investment embodied in the broadside mill which is yielding no continuous return.

The object of my invention is to avoid and overcome the foregoing and other difficulties of prior known methods and apparatus for the manufacture of metal blanks and slabs by the provision of

improved means and methods which are adapted to reduce or spread the ingot to the desired width before rolling to the desired blank or slab thickness. Another object of my invention is to provide processes and apparatus for reducing a slab or even an ingot to rough-sheet or strip form entirely in a single mechanism so that there will be no idle apparatus during any part of a strip-forming process. A more specific object of the invention is to provide a single reversing mill which combines the functions of a broadside mill and a rough-sheet mill.

My invention is predicated upon my discovery that the features of a broadside mill and a universal reversing type of rough-sheet mill can be combined in a single mill wherein strip can be rolled in a single continuous process from a slab. More broadly I have found that an ingot can be spread by cross rolling to provide an ingot of a width greater than 65 inches which then can be rolled longitudinally to a slab of a width greater than 65 inches and of desired thickness thereby eliminating, if desired, the usual slabbing operations. The advantages of this method are that in producing the slab there is abundant heat, as the total time of rolling and the final thickness of the slab are such as to leave no anxiety as to the finishing temperature. Another advantage is that, having spread the ingot, the slab is of the desired width when leaving the slabbing mill and can be cut to any length convenient for reheating or can be passed directly into the finishing mill if the final product is sufficiently thick to permit finish rolling on the initial heat.

The improved apparatus of my invention briefly comprises a combined broadside mill and rough-sheet mill upon which both of the operations performed on these mills can readily and continuously be performed. The horizontally journaled rolls of the combination mill are of sufficient width to make one or more broadside passes on either (1) an ingot or (2) the slab pieces cut from an ordinary ingot slab, with the pieces being then passed lengthwise through the same horizontal rolls which then function as a rough-sheet mill. Vertically journaled edging rolls are adjustably associated with the horizontal rolls and these are moved to engage with the edges of the slab piece during the rough-sheeting operation but are positioned during the broadside pass beyond the ends of the slab piece.

In the practice of the broad method of my invention I may work directly from a hot ingot by cross rolling it to spread it to a desired width. The ingot is then rolled longitudinally to a slab

of the desired thickness which can be handled further in any of the usual ways to produce a desired product, such as metal strip. Second, I may start with a slab produced in standard fashion which is reheated and passed broadside through horizontal rolls which engage the top and bottom of the piece to form it to width. One or more passes may, of course, be taken in a broadside direction to achieve this result. Edging rolls are 5 adjustably positioned beyond the ends of the slab piece during the broadside pass so that the full width of the horizontal rolls can be utilized if necessary in the broadside pass. The piece is then turned lengthwise and passed through the horizontal rolls which are periodically reversed, with the requisite number of passes being taken to form the slab to the desired thickness. The vertical edging rolls are moved to contact the edges of the slab piece during the lengthwise rolling of 10 the slab piece and these rolls control the width of the strip produced.

Apparatus which may be used in the practice of my invention, as just explained, is illustrated in the accompanying drawings, of which Fig. 1 15 is a diagrammatic plan view of the arrangement of one embodiment of my improved combination mill and associated apparatus; Fig. 1a is a diagrammatic plan view of a portion of Fig. 1 and illustrates a modification of the invention; Fig. 2 is an enlarged plan view of the rolling mill illustrated diagrammatically in Fig. 1; Fig. 3 is a longitudinal vertical cross-sectional view taken on line III—III of Fig. 2 and shows details of the mill structure; Fig. 4 is a transverse vertical sectional view taken on line IV—IV of Fig. 2 and indicates structure of the edging rolls; Fig. 5 is a sectional view taken on line V—V of Fig. 4 and illustrates the construction of the supporting rollers positioned between the edging rolls; and 20 Fig. 6 is a view similar to Fig. 2 but of a modification of my invention.

General assembly of apparatus

The arrangement of the apparatus of my improved strip-rolling equipment is illustrated diagrammatically in Fig. 1, in which the numeral 10 indicates generally a conveyor having rollers 11 reversibly driven by motors 13, which conveyor extends on both sides of the combination mill shown generally at 12. Associated with the conveyor 10 are furnaces 14 which are adapted to receive ingots or slabs (hereinafter called metal blanks wherever either ingots, slabs or the like are intended to be included). The furnaces 14 25 function to reheat the blanks and to deposit them in turn upon the conveyor 10 through the operation of suitable magazine pushers 15 associated with the furnaces 14. The conveyor 10 feeds the blanks in turn to the mill 12 and, after 30 the broadside and sheet-roughing passes, the conveyor carries the strip to any equipment adapted to perform the finishing operations thereon. In the embodiment of the invention illustrated, the rough sheet or strip is carried by 35 the conveyor 10 to a coiler, indicated generally by the numeral 17, which coils the strip in known manner with the strip being then transferred to any apparatus to have the final operations performed thereon. However, as seen in Fig. 1a, the 40 strip-finishing equipment may include a continuous or tandem mill 18 for cold or hot-rolling the strip to final dimensions with or without reheating or annealing. The tandem mills 18 of this modification are placed along the conveyor 10 in place of the coiler 17 as will be understood.

Horizontal roll stand

Referring to Figs. 2 and 3, which illustrate in greater detail the construction of the combination mill 12, a housing 20 having four corner columns journals, in bearing structure of standard design and adjustability, a pair of work-engaging rolls 21 of relatively small diameter but of a length sufficient to make a broadside pass on the metal blanks and to receive the widest strip to be rolled. The diameter of the rolls 21 is kept as small as possible to obtain lengthening rather than compressing and widening of the material worked during the rolling operation. The work-engaging rolls 21 are backed by supporting rolls 22 which are likewise journaled, in bearing structure of standard design and adjustability, in the housing frame 20. Suitable means, such as motor 25 and drive mechanism 26, are employed to drive the various working rolls. The motor 25 is adapted to be periodically reversed by known means to form the so-called universal or reversing type of mill.

Slab pushers

Associated with the combination mill are suitable pushers for moving the metal blanks broadside into the rolls 21. These means may take a number of forms but are preferably of such character that they can be moved out of the way during the lengthwise rolling operation and yet can be readily brought into play to positively move the blank broadside into the mill. As best seen in Fig. 3, these means comprise, in the form of the invention illustrated, arms 30 pivotally mounted at 31 upon suitable carriages 32 which are moved toward and from the roll stand by the provision of rack and gear mechanism indicated by the numeral 33 and operable by a prime mover (not shown). Similar pushing mechanism is provided on each side of the roll stand.

Edging rolls

Positioned on each side of the horizontal rolls 21 and 22 are vertically journaled edging rolls 40. These edging rolls are mounted so that they can be positioned beyond the ends of the horizontal rolls during the broadside pass, and so that they can be readily brought into engagement with the edges of the rough sheet or the slab piece during the lengthwise rolling thereof to exactly control the width of the strip. This function is achieved, in the particular form of the invention illustrated, by providing a frame 41 at each side of the horizontal rolls with the frame extending transversely of the conveyor 10. Each frame 41 is adapted to slidably carry a pair of boxes 42 each of which journals a stud shaft 43 upon which an edging roll 40 is keyed. A gear 44 is also keyed on the stud shaft 43 and this gear is driven by a gear 45 secured to the shaft 46 and likewise journaled in the housing. The shaft 46 has a bevel gear 47 secured to its lower end. To drive the bevel gear 47 and thus the edging roll 40, a drive shaft 50 is journaled at its ends in the frame 41 and is formed with a splined length which carries a bevel gear 51 which engages with the bevel gear 47. Each shaft 50 is driven by a reversible motor 52 through suitable reduction gear means 53.

Each housing 42 mounted on the frame 41 is adapted to be exactly controlled as to position to properly locate its edging roll 40, and this is achieved by the provision of a screw 55 which is secured to the housing 42 and which has a worm gear 56 threaded thereon and journaled in the frame 41. A worm 57 functions to turn the worm 75

gear 56 and adjust the housings 42 inwardly or outwardly of the frame 41. The worm 57 is driven by any suitable prime mover, such as motor 58, controlled by the mill operator.

5 In operating strictly on ingots the edging rolls are preferably moved somewhat away from the horizontal rolls so that the turntables (hereinafter described) can be positioned between the edging rolls and the horizontal rolls, all as illustrated in Fig. 6. Since the parts in Fig. 6 are similar to those of Fig. 2, although differently positioned, they have been indicated by like numerals.

15 Conveyor between edging rolls

15 Rollers for supporting the metal blank between the edging rolls are provided, and these rollers are preferably automatically adjusted so that, regardless of the distance between the edging rolls, the blank is properly supported. In the embodiment of the invention illustrated, the supporting rollers are carried on shafts 70 driven by motors 75. The shafts 70 are journaled at their ends in the frame 41 and supported near their middle portions by a bearing 71 carried on a transverse bar 72 formed on the frame 41. Bearings 74 for the shaft 70 are likewise formed on the ends of the housings 42 and these bearings not only receive the shaft 70 but likewise journal a sleeve 76 having flanged ends, one of which comprises a roller 77 and the other a flange 73. Thus while the sleeves 76 can rotate in and move longitudinally of the bearings 74 the flanged ends prevent the sleeves from moving out of the bearings. The sleeve 76 and associated roller 77 have a sliding fit on and are driven with the shaft 70. To insure a positive drive, the shaft 70 is polygonal in cross-section and is received in a similar bore in the roller 77 and sleeve 73. Rotary bushings are employed in the bearing 71 to take care of the polygonal shaft 70. A roller 79 is also preferably provided between the spaced shafts 70, and as shown in Fig. 5 this roller is journaled on bar 72.

40 In the movement of the edging rolls 40 towards each other the bearings 74 slide over the sleeves 76 until the bearings strike the rollers 77. Further movement of the rolls 40 towards each other carries the rollers 77 inwardly or towards each other until this movement and the inward movement of the rolls 40 is limited by the rollers 77 striking the bearings 71. At this time the rolls 40 and the rollers 77 are in the dotted line positions indicated in Fig. 5. Now when the rolls 40 are moved apart, the bearings 74 slide over the sleeves 76 until the bearings 74 engage with the collars 73 on the ends of the sleeves. Further outward or apart movement of the rolls 40 moves the sleeves 76 and rollers 77 away from the bearings 71 and into a desired adjusted position, as, 45 for example, that shown in full lines in Figs. 4 and 5.

50 Turntables

55 Associated with the conveyor 10 on each side of the combination mill are turntables indicated generally by the numeral 80. These turntables are of standard design and, as controlled by the operator, function to move up from below the surface of the rollers 11 on the conveyor 10 to 60 pick up and turn a metal blank to the desired angle to make the broadside, lengthwise or other angle pass. The tables are then lowered and leave the blank on the conveyor in its new position. When working with blanks in the form of ingots the turntables 80 are preferably placed as

close to the combination mill 12 as possible. In the drawings the assembly has been shown for handling blanks in the nature of slabs although ingots may also be handled.

5 Operation and process

10 The operation of the apparatus just described and the method of the invention briefly comprise forming a metal blank, heating the blank and running the blank broadside through the horizontal rolls to form the blank to the desired width. The means driving the horizontal rolls as well as the conveyor rolls 11 are periodically reversed so that any requisite number of passes may be made on the blank to form it to the proper 15 width for rough-sheet rolling, for example. The broadside pass on the blank increases the width of the piece to substantially the width of the rough sheet or strip to be rolled. During the broadside pass the vertical edging rolls are positioned laterally beyond the ends of the blank and even beyond the ends of the horizontal rolls.

20 After the broadside pass or passes, the blank is turned lengthwise by means of the turntables 80 associated with each side of the horizontal rolls, 25 and the vertical edging rolls are moved inwardly and against the side edges of the blank so that during the rough-sheeting operation the edges of the blank are kept to the proper dimensions by the edging rolls. The blank is now passed back 30 and forth through the reversing horizontal and edging rolls the requisite number of times to form the piece to rough-sheet form of the desired thickness and width. Of course, the horizontal rolls are periodically moved closer together to 35 effect the desired reduction in the thickness of the blank. Likewise, the vertical edging rolls can be adjusted from time to time to obtain the proper width in rough sheet.

40 The rough sheet may, of course, be of substantially any thickness and may even be termed a finished product after the rough-sheeting operation, with or without annealing, shearing and edge-trimming operations. However, in the preferred manner of practicing the invention, the 45 rough sheet is passed to the coiler 11, associated with the conveyor 10, and is coiled in known manner prior to further working operations thereon. For example, the coils can be annealed or reheated with subsequent cold or hot-rolling operations thereon to form the sheet or strip to the exact dimensions and characteristics desired. Instead of passing the rough sheet to the coiler 11, the invention contemplates passing it directly to the tandem or continuous mill 18 as seen in Fig. 55 1a for finishing operations.

50 As will be evident, my improved method contemplates working directly from an ingot which is rolled longitudinally to remove the taper but not sufficient to elongate the ingot beyond the 60 width of the horizontal rolls, cross rolled in horizontal rolls to width, and then rolled longitudinally as above described. Also I may roll the ingot in accordance with standard prior art practice to form a slab, shear the slab into pieces, reheat the pieces and handle the slab pieces by cross rolling to width and then longitudinally rolling on the same mill.

65 In working directly from an ingot it may be found advantageous to shear the slab produced 70 from the ingot into smaller pieces with subsequent reheating before finishing operations in any desired manner, as for example, on the combination mill 12 or on the continuous mill 18. However, if the slab produced from the ingot is of 75

sufficient size and retains the requisite amount of heat it may be finished without reheating as will be understood.

Summary

5 From the foregoing description of the method and apparatus particularly disclosed, it will be recognized that a combined broadside and sheet-roughing mill has been provided which will function to form strip or sheet of the desired dimensions and characteristics in a rapid, continuous manner. The combination mill involves much less initial investment than the standard installation of a separate broadside mill and separate sheet-roughing mills of the reversing or continuous type. There is no apparatus or separate mill standing idle for considerable periods during the production of rough sheet or strip, and floor space requirements as well as production costs are likewise reduced. The combination of completely 10 retractable, vertical edging rolls with horizontal rolls sufficiently long to make a broadside pass, and likewise being adapted to reversing sheet-roughing operations wherein the vertical edging rolls are moved into contact with the edges of 15 the sheet, constitutes a distinct improvement in strip and sheet-rolling methods because of investment and production savings.

Although the invention has been described as particularly applied to the making of sheet and 20 strip the principles of the invention are broadly applicable to the manufacture of other metal bodies as will be recognized.

While, in accordance with the patent statutes, one embodiment of the apparatus and several 25 ways of practicing the invention have been illustrated and described in detail, it should be understood that the invention is not limited thereto or thereby but is defined in the appended claims.

40 I claim:

1. That method of forming strip which comprises rolling an ingot to form a slab, cutting the slab to form a piece adapted to be rolled to strip of the desired width, reheating the slab piece, 45 running the piece broadside through the horizontal rolls of a broadside mill to form the piece to width, turning the rolled piece ninety degrees, adjusting vertical rolls associated with the mill so they engage the sides of the slab piece and the 50 horizontal rolls so they engage the top and bottom of the piece, and rolling the piece to strip form of the desired width and thickness by a reversing operation of the horizontal rolls with periodic reductions in the pass clearance of the 55 horizontal rolls.

2. The method of forming metallic sheet which includes rolling an ingot to form a slab, shearing a piece from the slab, reheating the sheared piece, rolling the sheared piece broadside in a mill to 60 increase the width of the piece to the desired dimensions, turning the piece and rolling it lengthwise through the same mill, periodically reversing the rolling operation while concurrently reducing the pass in a direction to form a sheet 65 of the desired thickness, and confining and rolling the edges of the piece during the last-named rolling operation to obtain a sheet of the desired width.

3. The method of forming metallic sheet which 70 includes rolling an ingot to form a slab, shearing a piece from the slab, rolling the sheared piece broadside in a mill to increase the width of the piece to the desired dimensions, turning the piece and rolling it lengthwise through the same mill, 75 and confining and rolling the edges of the piece

during the last-named rolling operation to obtain a sheet of the desired width.

4. The process of manufacturing steel strip which comprises rolling a steel blank broadside in a broadside mill to increase the width of the blank to more than about 65 inches and then rolling the blank longitudinally in the same mill to provide strip of the desired thickness, maintaining the width of the blank substantially constant during the last-named rolling operation, 10 and passing the strip thus formed directly to a tandem finishing mill.

5. That method of making metal strip which comprises forming a slab by a rolling operation, shearing a piece from the slab, passing the slab piece broadside through a reversing horizontal roll mill having associated vertical edging rolls but with the edging rolls being moved back so as to not interfere with the broadside pass, repeating this pass until the width of the slab piece is of the desired dimension, turning the slab lengthwise and passing the slab piece through the rolls in reversing passes to obtain a strip of the desired thickness, and adjusting the edge rolls 20 to engage the edges of the piece during the strip rolling.

6. That method of making metal strip which comprises forming a slab, shearing a piece from the slab, passing the slab piece broadside through a reversing horizontal roll mill having associated vertical edging rolls but with the edging rolls being moved back so as to not interfere with the broadside pass, repeating this pass until the width of the slab piece is of the desired dimension, turning the slab lengthwise and passing the slab piece through the rolls in reversing passes to obtain a strip of the desired thickness, and adjusting the edge rolls to engage the edges of the piece during at least part of the strip rolling.

7. The combination in a single mill of a broadside mill and a rough-sheet mill which includes horizontally journaled rolls of a length sufficient to roll the widest sheet and to receive the broadside pass, vertically journaled rolls for rolling the edges of the sheet during the sheet roughing, means for reversibly driving the rolls, and means adjustably mounting the edging rolls whereby they can be positioned beyond the ends of the horizontal rolls to leave the full width of the rolls accessible for a broadside pass or so they can be positioned within the ends of the horizontal rolls to engage the edges of the sheet during the sheet roughing.

8. The combination in a single mill of horizontal rolls of sufficient length to comprise a broadside mill and adapted to give a broadside pass to a slab, edging rolls for rolling the edges of the slab in the lengthwise pass of the slab to rough form strip, means adjustably mounting the edging rolls whereby they can be moved to the outside of the ends of the horizontal rolls during the broadside pass, and means for reversibly driving the rolls.

9. That method of forming strip which comprises heating a steel blank, running the blank broadside through the horizontal rolls of a broadside mill to form the blank to width, turning the rolled blank ninety degrees, adjusting vertical rolls so they engage the sides of the blank and the horizontal rolls so they engage the top and bottom of the blank, and rolling the blank to strip form of the desired width and thickness by a reversing operation of the horizontal rolls with periodic reductions in the pass clearance of the horizontal rolls.

10. The method of forming metallic sheet which includes heating a metal ingot having a width of less than 65 inches and a length of over 65 inches, rolling the ingot broadside in a mill to increase the width of the ingot to over 65 inches, turning the ingot and rolling it lengthwise through the same mill, periodically reversing the rolling operation while concurrently reducing the pass in a direction to form a sheet of the desired 10 thickness, and confining and rolling the edges of the ingot during the last-named rolling operation to obtain a sheet of the desired width.

11. The method of forming steel sheet which includes rolling a metal blank broadside in a broadside mill to increase the width of the blank to the desired dimensions, turning the blank and rolling it lengthwise through the same mill, and confining and rolling the edges of the blank during the last-named rolling operation to obtain a 20 sheet of the desired width.

12. The method of forming steel members which includes reheating a full-sized steel ingot, rolling the ingot broadside in a broadside mill to increase the width of the ingot to the desired dimensions, turning the ingot and rolling it lengthwise through the same mill, periodically reversing the rolling operation while concurrently reducing the pass in a direction to form a member of the desired thickness, and confining and 30 rolling the edges of the member during the last-named rolling operation.

13. The process of manufacturing metal strip which comprises rolling a metal blank broadside in a reversing mill to increase the width of the blank to over about 65 inches, rolling the blank in the same mill to provide strip of the desired thickness, and maintaining the width of the strip substantially constant during the last-named rolling operation.

14. That method of making metal strip which comprises reheating an ingot, longitudinally rolling the ingot to remove its taper but not sufficient to elongate the ingot beyond the width of the horizontal rolls of a reversing broadside mill, 40 passing the ingot broadside through a reversing broadside mill having associated vertical edging rolls but with the edging rolls being moved back so as to not interfere with the broadside pass, repeating this pass until the width of the ingot is of the desired dimension, turning the ingot lengthwise and passing it through the rolls in reversing passes to obtain a strip of the desired thickness, and adjusting the edge rolls to engage the edges of the strip during the strip rolling.

15. That method of making metal bodies which comprises reheating and longitudinally rolling an ingot to remove its taper but without noticeably increasing its length, rolling the ingot broadside to a width suitable for producing a desired body, and longitudinally rolling the ingot while confining the edges of the ingot to form a body of the desired dimensions.

16. That method of manufacturing metal blanks which comprises casting a tapered ingot, reheating the ingot, rolling the ingot longitudinally in a mill to remove the taper, turning the ingot through ninety degrees in a horizontal

plane and about a vertical axis, rolling the ingot broadside in the same mill to increase its width to a desired width, turning the ingot through ninety degrees in a horizontal plane and about a vertical axis, rolling the ingot longitudinally in the same mill to produce a blank of the desired thickness, and maintaining the width of the blank as desired during the last-named rolling operation.

17. Apparatus for directly rolling a metal ingot into a blank comprising a combined broadside and roughing mill having working rolls on horizontal axes of a length greater than the length of an ingot to be worked whereby the entire ingot can be passed broadside through the mill to increase the width of the ingot to substantially that of the blank to be rough formed, edging rolls on vertical axes positioned adjacent the horizontal rolls for maintaining the width of the blank as desired, and a turntable positioned 20 between the edging rolls and the horizontal rolls for turning the ingot to provide a broadside or a longitudinal rolling operation.

18. Apparatus for directly rolling steel ingots to blanks of desired dimensions comprising a roll stand of a roll length capable of receiving an ingot broadside, a conveyor extending to and from the mill and substantially of the width of the stand, a pusher associated with the stand for moving an ingot into the stand, a turntable 30 on the conveyor in front of the stand and capable of turning the ingot either broadside or longitudinal to the stand, and edging means positioned on both sides of the conveyor and adjustable to and from each other, said edging means being 35 positioned closely adjacent the turntable but not interfering with the operation thereof.

19. In combination, means for rolling a full-sized steel ingot either broadside or longitudinally, means for edging the ingot during longitudinal rolling, and means positioned between the edging means and the rolling means for turning the ingot to present it either broadside or longitudinally to the rolling means.

20. That method of making a metal blank directly from a full-sized hot steel ingot which includes the steps of longitudinally rolling the ingot to remove its taper but without noticeably increasing its length, rolling the complete ingot broadside to increase it to a desired width, and 40 rolling the ingot lengthwise to desired thickness.

21. Apparatus for directly rolling a metal ingot into a blank comprising a combined broadside and roughing mill having working rolls on horizontal axes of a length greater than the length 55 of an ingot to be worked whereby the entire ingot can be passed broadside through the mill to increase the width of the ingot to substantially that of the blank to be rough formed, edging rolls on vertical axes positioned adjacent the horizontal rolls for maintaining the width of the blank as desired, and turntables positioned at opposite sides of the mill for turning the ingot to provide a broadside or a longitudinal rolling operation.

KIRTLAND C. GARDNER. 65
